TOY BOMB

Harry Callen, Chicago, Ill., assignor to Callen Manufacturing Corporation, Maywood, Ill.

Application November 29, 1949, Serial No. 130,031

1. Claim. (Cl. 46—200)

1

My invention relates to toys which are adapted to be thrown or struck to secure the firing of a paper ammunition cap. One well known form of such a toy is the firing cane, in which a cap is inserted near the bottom and the cane struck against the pavement to accomplish the firing of the cap. Another such toy is a small device in which the cap is inserted before the device is tossed or thrown to the ground. In both cases, the receptacle for the cap is inadequate to insure the retention of the cap when the firing of the same takes place, and in the case of the cane, cleaning out of the exploded cap is difficult. It is therefore one object of the present invention to provide a toy in the nature of a bomb which contains means to confine the cap in the firing zone before the toy is thrown or dropped, so that the escape or loss of the cap is prevented when the firing action takes place.

A further object is to provide a toy of the above character which forms a single and compact unit when in use.

Another object is to design the novel toy on lines of sturdiness and extreme simplicity, in order that no difficulty may be experienced during its handling or use.

An additional object is to design a toy of the above character whose components are locked when the firing of the cap takes place, and cannot be separated by the force of the firing action.

An important object is to construct the novel toy with a minimum number of parts consistent with its efficient construction and function, whereby to make the manufacture of the toy inexpensive.

With the above objects in view, and any others which may suggest themselves from the description to follow, a better understanding of the invention may be had by reference to the accompanying drawing, in which—

Fig. 1 is an elevation of the toy in the bomb form while in the normal position prior to use;

Fig. 2 is a similar view, showing the toy set for use;

Figs. 3 and 4 are, respectively, enlarged sections on the lines 3—3 and 4—4 of Figs. 1 and 2;

Figs. 5 and 6 are views similar to Figs. 1 and 2, showing a modification of the toy in the form of a firing cane, portions of the latter being broken away; and

Fig. 7 is a fragmental view of a conventional sheet of ammunition caps.

Referring specifically to the drawing, the novel toy is essentially in bulbous form to simulate an aerial torpedo. Structurally, the toy is composed

2

of an upper section 10 and a lower one 11. Both sections are of cast metal, and the shank of the upper one is preferably bored as indicated at 12 to receive a plug 13 from the base 14 of a tail-piece 15 which is formed with the usual vanes 16 in simulation of the direction stabilizer of an aerial torpedo; or the tail piece may be made integrally with the section 10.

The upper section 10 is formed with a conical skirt 20 simulating a bell; and the bottom surface of the shank 10 is made flat, as suggested at 21.

The lower section 11 of the toy is designed to serve as a hammer in respect to the anvil formed by the bottom 21 of the upper section. Thus, the hammer is designed to be positioned normally in spaced relation to the anvil 21, as indicated in Fig. 1, leaving a space in which a cap 24 torn from a typical sheet 25 of ammunition caps may be inserted. The caps are defined by longitudinal and transverse perforation lines 26, so that each cap torn away is of substantially square form and capable of direct insertion between the hammer and anvil of the toy as indicated in Fig. 3.

The hammer 11 is designed to be supported from the section 10 by means consisting of a cross-pin 30 driven diametrically through the hammer and projecting from its sides, the end portions of the cross-pin cooperating with cams 31 formed in the walls of the bell 20. The cams form the floors of openings 33 communicating with the space in which the ammunition cap 24 is inserted. Also, the cams are of climbing form, with dwells 36 approaching a horizontal course. It is thus apparent from Figs. 1 and 2 that the partial rotation of the hammer base 27 in the direction indicated by the horizontal arrow will cause the pins 30 to climb the cams 31 and advance the hammer 11 in the direction of the anvil 21. Actually, the ammunition caps are much thinner than shown, so that eventually the cap shown inserted in Fig. 1 and subjected to the advance of the hammer 11 will be tightly compressed when the hammer has turned to the position of Fig. 2, where the pin 30 is in engagement with the dwells 36 and locks the hammer to the cap and anvil by wedging action. The assembly of the toy is now in a single unit, so to speak, with the cap confined between the hammer and the anvil. Thus, when the toy is directed into impact with a floor, pavement or other unyielding surface, such impact will cause the explosion of the cap with a loud report, accomplishing the function of the toy. The same

result may be obtained when the toy is tossed upwardly into the air to simulate an aerial bomb upon descent, or when the toy is thrown with its base in the direction of a wall or post. The toy may also be modified to receive the staff 40 of a conventional firing cane instead of the tail-piece 15. The modified form of the toy is illustrated in Figs. 5 and 6, and the toy will of course function by the usual operation of the cane.

The novel toy has a number of advantageous features. Thus, the normal separation of the hammer from the anvil leaves a sizable slot or passage between these parts for the easy insertion of the ammunition cap, the meeting surfaces of the hammer and anvil being of sufficient size to overlie the medial or active portion of the cap. The base 27 then forms a convenient knob which may be rotated as previously described to firmly compress the cap between the hammer and anvil, so that the cap is fully confined between these parts. Further, the nature of the cams 31 is such as to impose a wedging and positive locking effect on the hammer, to the end that the same cannot loosen or creep into its former free state to expose the cap. The toy thus becomes a solid assembly by the adjustment just described, so that the cap cannot escape before it is fired; and its explosion is confined between the hammer and anvil during the firing action. Yet, a simple return twist of the base 27 after the toy has been fired retracts the hammer sufficiently to permit its burned cap to be ejected with a fingernail, shaken out, or by the insertion of a new cap from behind. Further, it will be realized that the locking of the hammer to the anvil is positive to the extent of maintaining these parts fixed against the maximum explosive force of the cap, so that such force cannot cause the toy to separate or fly apart to possibly injure surrounding persons or objects. The toy is therefore simple and safe to operate; and the nature of its parts enables it to be manufactured at low cost. Finally, it will be noted that the base 27 is enlarged from the hammer to combine with the section 10 as 45 a bulbous body simulating an aerial bomb.

While I have described the invention along specific lines, various minor changes or refinements may be made therein without departing from its principle, and I reserve the right to employ all such changes and refinements as may come within the scope and spirit of the appended claim.

I claim:

10 A toy bomb comprising an upper stem having an enlarged recessed base, opposite wall portions of the latter being cut away to form oppositely-inclined cam surfaces which are steep along one portion and relatively flat along another portion, an anvil at the bottom of the stem 15 within the upper part of the base recess, a hammer movable in the recess relative to the anvil and having an enlarged base, a pin passing through the hammer and having end portions engaging the cam surfaces, a space being provided for the insertion of an ammunition cap when the hammer and the anvil are spaced apart, whereby the hammer on rotation in one direction advances toward the anvil and compresses the cap thereagainst, the compressing 20 action being effected when said end portions are in engagement with the relatively flat cam surfaces to hold the hammer in close proximity to the anvil, the striking of the hammer base by or against an external object operating to detonate the cap, the hammer then being rotatable in reverse direction to facilitate the removal of the exploded cap from said space, and the hammer being inseparable from the stem base.

HARRY CALLEN.
